UNITED STATES PATENT OFFICE

CHARLES F. L. KAUFMANN, CARL H. KAUFMANN, AND WALLER L. KAUFMANN, OF
SANTA ANA, CALIFORNIA.

DESIGN FOR A VEHICLE-LAMP BRACKET.

53,177.

Specification for Design.

Patented Apr. 8, 1919.

Application filed January 22, 1918. Serial No. 213,253. Term of patent 7 years.

To all whom it may concern:

Be it known that we, CHARLES F. L. KAUFMANN, CARL H. KAUFMANN, and WALLER L. KAUFMANN, citizens of the United States, residing at Santa Ana, in the county of Orange and State of California, have invented a new, original, and ornamental Design for a Vehicle-Lamp Bracket, of which the following is a specification, reference being had to the accompanying drawing, forming part thereof.

Figure 1 is a rear view of the vehicle lamp bracket, showing our new design.

Fig. 2 is a side elevation thereof.

We claim:

The ornamental design for a vehicle lamp bracket, as shown.

CHARLES F. L. KAUFMANN.
CARL H. KAUFMANN.
WALLER L. KAUFMANN.
